UNITED STATES PATENT OFFICE.

BENJAMIN LIPPER, OF PHILADELPHIA, PENNSYLVANIA, ASSIGNOR TO AUGUSTUS A. LAZARUS, ISAAC A. SCHWARZ, AND BENJAMIN LIPPER, OF SAME PLACE.

DESIGN FOR A DRESS-TRIMMING.

SPECIFICATION forming part of Design No. 21,237, dated December 15, 1891.

Application filed November 12, 1891. Serial No. 411,745. Term of patent 3½ years.

To all whom it may concern:

Be it known that I, BENJAMIN LIPPER, a citizen of the United States, and a resident of Philadelphia, Pennsylvania, have invented a
5 Design for a Dress-Trimming, of which the following is a specification.

My design is fully shown in the accompanying drawing, which represents a view of a piece of trimming embodying the design.

10 The trimming has a tape-like heading *a*, with flat ribbon-like pendants *b*. These ribbon-like pendants have looped or fringed edges, and the tape-like heading is crossed at intervals by a cord *d*, which forms loops above
15 the heading; but said cord and the fringed edges of the pendants are to be regarded as subsidiary features of the design, the main

feature of the same being the heading with the flat ribbon-like pendants. These pendants may also be provided at the lower ends 20 with drops or tassels, as shown, for instance, by dotted lines, without departing from the essential characteristics of the design.

I claim—

The design for a dress-trimming, substantially as described, and as shown in the accompanying drawing. 25

In testimony whereof I have signed my name to this specification in the presence of two subscribing witnesses.

BENJAMIN LIPPER.

Witnesses:

EUGENE ELTERICH,
HARRY SMITH.
